UNITED STATES PATENT OFFICE

149,299

DESIGN FOR AN ELECTRIC IRRADIATION
DEVICE OR THE LIKE

Jules Radinsky, Seattle, Wash.

Application May 6, 1946, Serial No. 129,360

Term of patent 3½ years

Cl. D48—20

To all whom it may concern:

Be it known that Jules Radinsky, a citizen of the United States, residing at Seattle, Washington, has invented a new, original, and ornamental Design for an Electric Irradiation Device or the like, of which the following is a specification, reference being had to the accompanying drawing, forming a part thereof, in which

Fig. 1 is a perspective view of an electric irradiation device or the like showing my new design;

Fig. 2 is a plan view of the device of Fig. 1; and

Fig. 3 and Fig. 4 are rear and side views, respectively, of the device shown in Fig. 1.

I claim:

The ornamental design for an electric irradiation device, or the like, as shown.

JULES RADINSKY.
